UNITED STATES PATENT OFFICE

FRANK B. BELL, OF PITTSBURGH, PENNSYLVANIA

KEY BOLT

Application filed August 1, 1927. Serial No. 209,725.

The invention relates in general to key-bolts and has particular reference to a key-bolt of the type comprising a bolt and a key adapted to be driven through a slotted portion of the bolt and to engage and be bent by an offset portion of the bolt into locked engagement in the slotted portion to provide an automatic self-locking key. My invention contemplates a construction wherein the key is sufficiently rugged and adapted to support heavy elements in engaged position on the shank of the bolt.

The principal object of the invention is the provision of a self-locking key-bolt construction in which the parts are of simple and inexpensive, yet rugged construction and are adapted to sustain relatively heavy loads without shearing off.

Another important object of the invention is the provision of a key-bolt construction including a slotted bolt shank, the slot of which is arranged to receive and to deform the key as the latter is forced into position in order to lock the key in engaged position.

Another important object of the invention is the provision of a bolt and a key adapted to lock itself in engaged position and in the bolt as it is driven through a slotted portion of the bolt shank.

Still another important object of the invention is the provision of a key-bolt construction comprising a bolt having a slotted shank and a key comprising a rectangular strip adapted for assembly through the slotted bolt shank and to lie in a plane parallel with the longitudinal axis of the bolt shank and be deformed thereby as it is arranged in assembled position, in order to provide for automatically locking the bolt in place.

Numerous other objects and advantages of the invention will be apparent as it is better understood from the following description, which, taken in connection with the accompanying drawings, discloses a preferred embodiment thereof.

Referring to the drawings:

Figure 1 is a perspective view of a key-bolt, parts of which are shown in section to illustrate the details of construction of the slotted portion;

Fig. 2 is a section taken along line 2-2 in Fig. 1;

Fig. 3 is a perspective view of a key for use in conjunction with the key-bolt embodying my invention; and

Fig. 4 is a perspective view of the key-bolt and key in assembled position in the bolt.

To illustrate my invention, I have shown on the drawings a bolt comprising a shank 11 and a head 12. A rectangular slot or aperture 13, having upper and lower sides 14 and 15 lying in planes normal to the longitudinal axis of the bolt, is formed through the shank 11 adjacent the lower end and forms a rectangular opening 16 at one side of the bolt, the lateral sides 17 of the slot lying in planes substantially parallel with the longitudinal axis of the bolt.

The slot 13 comprises two parts, 18 and 22, lying adjacently between the upper and lower sides 14 and 15 of the slot. The portion 18 comprises the main portion of the slot and extends directly through the bolt, intersecting the far side of the shank to form a rectangular opening 19. The lateral sides 21 of the portion 18 comprise plane surfaces and both slot portions 18 and 22 are aligned on the near side of the bolt and together form a rectangular entrance 16 to the slot. The slot portion 22 is relatively narrow, when compared with the slot portion 18, and comprises a curved passage through the bolt shank, the parts of the slot portion 22, adjacent the entrance 16 of the slot, being arranged parallel and in alignment with the main slot portion 18, and the remainder being offset therefrom commencing at a point 25 in the interior of the shank 11 and forming a shoulder 26 within the bolt. From the point 25, the slot portion 22 extends in an angular direction and intersects the surface of the bolt to form a rectangular opening 23 out of alignment with the opening 19 of the main slot portion 18 and displaced therefrom around the bolt

shank.

A key, adapted to engage in the slot 13, is provided and comprises a rectangular strip of iron 31, or other convenient key material of sufficient length to extend through the shank of the bolt and to protrude a substan-

tial distance on both sides, in order to engage beneath a member positioned between the key and the bolt head 12. The strip 31 is sufficiently wide between opposite edges 32 to engage between the upper and lower sides 14 and 15 of the slot 13, and is formed of stock sufficiently thick to engage between the lateral sides 17 of the slot when positioned therein. The strip is provided with a slot or kerf, formed therein, parallel with the sides 32 and extending from one end of the key to adjacent the other and terminating at an enlarged aperture 34 in the body of the key. This slot divides the lower portions of the key into two prong portions 35 and 36, the widths of which correspond with the widths, respectively, of the slot portions 18 and 22.

The key 14 is adapted to be driven into the slot 13, through the main opening 16, the portion 35 engaging in the slot portion 18 and the portion 36 engaging in the slot portion 22. As the key is forced into the slot, the end 37 of the prong portion 36 engages the shoulder 26, formed in the bolt by the displacement of the slot portion 22, and is forced through the offset part of the slot portion 22. The portion 36 is thus deformed or curled to conform with the shape of the offset slot portion as the key is driven into the slot; and the key assumes a final position, as shown in Fig. 4 of the drawing, when in fully-engaged position.

It will be manifest that this construction provides a self-locking key which may be engaged in a slotted bolt simply by driving it into engaged position in the slot, and which, when in final engaged position, cannot be displaced from the bolt without laboriously rebending the key. Since the key is arranged in the bolt shank with its longer sides parallel with the axis of the shank, it will be apparent that the key presents maximum resistance to downward pressures exerted upon its upper edge 32 from the direction of the bolt head 12 and thus provides a key construction having maximum strength. The construction described has great simplicity and strength, the cost of manufacture of the parts is correspondingly low, and, at the same time, a satisfactory self-locking key-bolt is provided.

It is thought that the invention and many of its attendant advantages will be understood from the foregoing description, and it will be apparent that many changes may be made in the form, construction and arrangement of the parts without departing from the spirit and scope of the invention or sacrificing all of its material advantages, the form hereinbefore described being merely a preferred embodiment thereof.

I claim:

1. In combination, a bolt having a slot extending transversely of it for receiving a key, said slot being divided into two parts arranged side by side axially of the bolt and

one of said parts being offset with respect to the direction of key movement, and a key arrangeable through said slot and having a part diverted to locking position by the offset part of said slot.

2. The combination of a bolt having a generally rectangular slot through it, an adjacent slot part having an offset exit, and a key of rectangular cross section arrangeable through the main and adjacent slot parts, said key being slit to permit a portion of it to be diverted through said offset exit of said slot.

3. The combination of a bolt having a generally rectangular slot through it, an adjacent slot part having an offset exit, and a key of rectangular cross section arrangeable through the main and adjacent slot parts, said key being slit to permit a portion of it to be diverted through said offset exit of said slot with the remainder of the key extending in undeformed condition through the main portion of said slot.
